UNITED STATES PATENT OFFICE.

ARTHUR RACICOT AND ALEXANDER N. RACICOT, OF WEBSTER, MASSACHUSETTS.

INSOLE.

1,265,514.

Specification of Letters Patent.

Patented May 7, 1918.

Application filed September 29, 1917. Serial No. 194,040.

To all whom it may concern:

Be it known that we, ARTHUR RACICOT and ALEXANDER N. RACICOT, citizens of the United States, residing at Webster, in the 5 county of Worcester and State of Massachusetts, have invented new and useful Improvements in Insoles, of which the following is a specification.

Our present invention pertains to insoles 10 for boots and shoes; and it consists in the peculiar and advantageous water-proof insole hereinafter described and definitely claimed.

In the accompanying drawings, which are 15 hereby made a part hereof:

Figure 1 is an inverted plan illustrative of an insole constructed in accordance with our invention.

Fig. 2 is a transverse section of the same, 20 taken in the plane indicated by the line 2—2 of Fig. 1.

Fig. 3 is an enlarged fragmentary transverse section showing a portion of an insole constructed in accordance with a modification 25 of our invention.

Referring by numeral to the said drawings and more particularly to Figs. 1 and 2 thereof:

1 indicates a layer which is preferably of 30 leather though it may be of any analogous material and is of about the proportional thickness illustrated, and 2 is a rib disposed on the underside of the forward portion of the layer 1 and spaced about the distance illustrated from the edge thereof. The 35 said rib 2 is formed by a cord or other suitable filler 3 and covering layers 4 and 5 arranged over the filler connected at 6 by a row of stitches to the layer 1; the said row 40 of stitches being disposed at the inner side of the rib as clearly shown in Figs. 1 and 2. The layer 5 is of textile material suitable to the purpose while the layer 4 is of rubber or rubber compound having the quality of 45 excluding water.

In the production of our improved insole, the layers of textile material and rubber together with the layer of leather or analogous material are vulcanized together in the ordinary well known manner or by a cold vulcanizing process, with the result that the several layers 1, 4 and 5, are converted into a unitary mass.

The insole produced in the manner de- 55 scribed is adapted to be incorporated in a shoe or boot, and to be connected with the

vamp and lining and the outer or tap sole in accordance with the McKay or Good-year methods and by either hand work or machinery, and when so incorporated the 60 insole will have the quality of being entirely water-proof. It will also be appreciated that the rib covered with layers of rubber and canvas or other textile material vulcanized together is of such character that with each 65 stitch taken through the covered rib, the rubber will expand incidental to the stitching and close tight against the thread so as to effectually prevent moisture from gaining access to the filler or to the underside of 70 the layer 1. It will further be appreciated that by virtue of our improved insole should the tap sole (not shown) become unstitched the water-proof quality of the shoe is not 75 affected, this for the reason that the insole is next to the foot of the wearer and even when disconnected to the tap sole will exclude water from the interior of the shoe.

While we have shown the embodiment in 80 Figs. 1 and 2 as comprising but one layer 4 and one layer 5, it is manifest that without involving departure from the scope of our invention any number of the said layers may be employed, according to the quality 85 of insole desired.

In the modification shown in Fig. 3, the sole or bottom is made up of a layer 1^a formed of alternate layers 4 and 5, of rubber or rubber compound and textile material, respectively, and the said layer 1^a is provided with a rib 2^a formed and disposed in the same manner as the rib 2 of Figs. 1 and 2; the formation of the said rib 2^a being accomplished by covering a filler 3, 90 of cord or other suitable material, with layers 4 and 5 of rubber and canvas or textile material, respectively.

It will be gathered from the foregoing 95 that when the embodiment shown in Fig. 3 is employed the layer 1^a is positioned next to the foot of the wearer; also, that the embodiment shown in Fig. 3 is possessed of all of the advantages hereinbefore ascribed to the embodiment shown in Figs. 1 and 2.

Having described our invention, what we 100 claim and desire to secure by Letters-Pat- 105 ent, is:

1. As a new article of manufacture, an insole for boots and shoes, comprising a bottom layer, a rib filler arranged against one side 110 of said layer, and layers of rubber and textile material arranged over the rib filler and

against the outer surface of the first-named layer and vulcanized together and to said first-named layer.

2. As a new article of manufacture, an 5 insole for boots and shoes, comprising a bottom layer made up of layers of rubber and textile material vulcanized together, a rib filler arranged against one side of said bottom layer, and layers of rubber and textile 10 material arranged over the rib filler and against the outer surface of the first-named

or bottom layer and vulcanized together and to said first named or bottom layer.

In testimony whereof we have hereunto set our hands in presence of two subscribing 15 witnesses.

ARTHUR RACICOT.

ALEXANDER N. RACICOT.
